DR D 17,859

Design No. 17,859, dated November 1, 1887.

UNITED STATES PATENT OFFICE.

JOHN SLATER, OF BURSLEM, COUNTY OF STAFFORD, ENGLAND.

DESIGN FOR DISHES.

SPECIFICATION forming part of Design No. 17,859, dated November 1, 1887.

Application filed September 7, 1887. Serial No. 249,058. Term of patent 7 years.

To all whom it may concern:

Be it known that I, JOHN SLATER, a subject of the Queen of England, residing at Burslem, Staffordshire, England, have invented a certain new and original Design for Dishes, fully described and represented in the following specification and the accompanying illustrations, forming a part of the same.

This invention relates to a design for the configuration and ornamentation of the various dishes or pieces composing a table-service.

The principal or characteristic feature of the design consists of a series of oblique or turbinate corrugations of ogee form which radiate from the center or axis of the dish or piece, but vanish both before reaching the center and the edge, so as to form a band or zone extending around the dish or piece.

In the case of the covered dishes of the service, both of the pieces composing the dish—that is, the dish proper and the cover—are provided with this configuration and ornamentation.

As a full understanding of the design can only be given by an illustration of a variety of dishes embodying the same, such illustration is herewith given.

In said illustrations, Figure 1 is a side view of a covered dish, Fig. 2 a top view of the cover, and Fig. 3 a top view of an oblong dish or platter, all embodying the design.

Referring to said figures, it will be seen that each of the dishes or pieces composing the dish

is provided with a band or zone of corrugations, 35 *a*, which extend entirely around the dish. These corrugations, which are oblique or turbinate and of ogee form, are arranged to radiate from the center of the dish or piece and vanish as they approach the center and the margin, so as to form the band or zone, as stated.

In the case of the covered dishes the corrugations are formed upon the outsides of the dish proper and the cover, as shown in Figs. 45 1 and 2, while in the case of the shallow flat dishes—such as plates and platters—they are arranged upon the inside, as shown in Fig. 3.

Only two of the principal dishes of a table-service are herein illustrated; but these are 50 deemed sufficient to convey a full understanding of the design, it being understood that the remaining dishes of the service embody the design in a similar manner.

What is claimed is—

A design for the configuration and ornamentation of dishes, consisting of a band or zone of turbinate or oblique radial corrugations of ogee form which vanish both before reaching the center and the edge of the piece, 60 substantially as shown and described.

In testimony whereof I have hereunto set my hand in the presence of two subscribing witnesses.

JNO. SLATER.

Witnesses:

JOHN W. LATIMER,
L. MAWDESLEY.
